UNITED STATES PATENT OFFICE.

WALTER S. MITCHELL, OF SAN FRANCISCO, CALIFORNIA.

REMOVABLE FLOORING-STRIP.

1,029,940.

Specification of Letters Patent. Patented June 18, 1912.

Application filed December 5, 1910. Serial No. 595,581.

To all whom it may concern:

Be it known that I, WALTER S. MITCHELL, citizen of the United States, residing in the city and county of San Francisco and State of California, have invented new and useful Improvements in Removable Flooring-Strips, of which the following is a specification.

This invention relates to flooring and particularly to a floor structure, embodying means in combination with a concrete floor for allowing the ready insertion and removal of electric and other wires, and gas, steam or air pipes.

Building regulations of certain municipalities require that electric wires, such as telephone, telegraph, signal and other electric conductors, be so protected when erected in a building as to prevent the action of moisture upon the wire. In other words the law requires wires to be so embedded as to be damp proof, and a simple and ready means whereby the wires may be removably erected and easily accessible so as to string or run them through iron pipes of suitable size is desired.

The object of this invention is to provide means whereby electric conductors may be properly embedded or protected from moisture by running them through suitable pipes or tubes removably laid in concrete floors; and to provide means whereby access may be had to the pipes to vary the connections or change their direction or length as may be required; and to provide in combination with the concrete floor a suitable flooring or carpet strip adapted to conceal the wire-containing pipes and at the same time provide means whereby the floor covering, as linoleum, carpet, or rug, may be easily secured upon the concrete floor.

The invention consists of the parts and the construction and combination of parts as hereinafter more fully described and claimed, having reference to the accompanying drawings in which—

Figure 1 is a perspective view of a fragment of a concrete floor, showing the concealed, protected wires and the removable flooring strip and a metallic sheeting. Fig. 2 shows a perspective view of a slightly modified form of the metallic sheeting or liner and the removable retaining strip. Fig. 3 shows another modification of the metallic liner in which one of its edges is

flanged to project over the contiguous wall of concrete. Fig. 4 is another modification in which the metallic liner is used on one side only.

In the present embodiment of my invention A represents a concrete floor of suitable thickness; B a vertical wall of a room along the lower portion of which is run a base-board 2, the lower edge of which is substantially in the same plane with the upper surface 3 of the concrete floor A.

In carrying out the principle of my invention, there are suitably formed in the floor A, channels or mortises 4 and 5; the channel 4 extending inwardly beneath the lower edge of the base-board 2 so as to form a small pocket or chamber for the reception of a tube or pipe 6, through which may be threaded electric conductors 7 which may be branched or terminated at any suitable point and brought up from the pipe 6 through the base-board, as shown at 8 in Fig. 1, so that connections may be made to the conductor 7, or through a strip to be hereinafter described.

The channel or mortise 5 may be made in the cement or concrete floor A at a suitable distance from the channel 4, as the size of the room or other conditions require, and may run parallel therewith or at any angle desired, but in Fig. 1, I have shown a fragment of flooring adjacent a corner of a room and which clearly shows the channel 5 as being laid parallel to the vertical walls of the room.

One or both of the vertical walls of the channels 5 may be formed with a concavity as 9, of approximately the same contour as the pipe or tube 6, which is to be laid in the channel, so that the vertical walls 9 of the channels 4 and 5 may be undercut so as to partially cover tube 6.

For the purpose of securely but removably fastening the wire-conducting tubes 6 in their respective pockets against the walls of the channels, I employ suitable strips or fillers 10, of wood or other material, cut into convenient lengths or blocks, as blocks 11, having one of their edges concaved as at 12, so as to form a seat against which the tubes 6 may snugly rest and the mean width of a strip 10 is approximately equal to the distance between the adjacent walls of the concealed tubes 6, and when firmly braced into the channels 4 or 5 the strips 10 form

a locking key or bar holding the tubes immovably in position against their respective seats in the channels.

5 A portion of the strip 10 is adapted to project beneath the lower edge of the base-board 2 any desired distance, and the walls of the floor A and the bottom edge of the base-board 2 and the concave edge 12 of the strip 10 form a pocket in which the pipe 6 is entirely concealed.

10 In order to facilitate a ready removal of the retaining strips or keys 10 from their respective channels, the edge opposite to the concaved edge 12 may be formed for a portion of its depth at substantially a right angle as 13, Fig. 3, to the upper plane or surface of the strip, or may be slightly concaved so as to embrace approximately a quarter of the tube 6, as shown at 14, Fig. 1. 15 In either event the remainder of this edge of the strip 10 is beveled back, as at 15, at a suitable angle and the strip 10 may then be swung upwardly about the pipe or tube 6 as a pivot, freely swinging out of the channel.

20 Manifestly the channels in the concrete floor A may be formed in any suitable manner, as during the original casting of the floor, in which event suitable molds would be inserted to form recesses and afterward removed, or, if desired, I may employ in carrying out my invention a suitably shaped metallic trough, one form of which is shown at 16 in Fig. 1, in which the trough has a 25 pair of upturned, curved, concave flanges as 17, whereby the concaved seats 9 may be formed in the concrete during the construction of the floor, and when this metallic trough is used, it not only facilitates the 30 formation of the channels, but also acts as a lining or reinforcement to the cement or concrete, so that when the retaining key or strip 10 is forced into position to force the pipes into their respective seats the adjacent 35 overhanging walls of the channels will be 40 protected.

45 Manifestly I am varying the form of the metallic lining 16 to conform to various conditions, and as shown in Fig. 4, the trough 50 16 may be provided at one of its edges with a projecting, longitudinal rib or flange 18 adapted to be passed into a suitably undercut channel or recess 19, in the floor A, and the pipe-receiving portions 17 of the trough 55 16 may be made substantially rectangular in cross section to receive the pipes 6, and the retaining, removable strips 10 press downwardly between the flat portions 20 of the trough to hold the pipes in position.

60 In Fig. 3 I have added to the trough an outwardly extending flange 21, shown as overlapping the adjacent overhanging wall of the channel 5; in this way protecting the wall against fracture.

65 By providing the wooden strips 10 for

removably securing the pipes 6 in position, the upper surface of the strips may be utilized for the purpose of nailing down carpet, linoleum, or such other floor covering as may be employed to cover the concrete 70 floor A.

The floor covering may either be secured to the inner set of strips covering the channel 5 or may be nailed to the set of strips which are laid under the base-board 2, and, 75 if so desired, there may be secured to the upper surface of the strip 10 adjacent the base-board 2 a finish strip as 22, against which the carpet or linoleum may be snugly fastened; the finishing strip 21 forming a 80 neat border around the carpet.

The tendency of the carpet nailed to the strips is to exert a strong pull on them and thus firmly hold them in place in the channels; the edges of the strips are concaved 85 and retained by the pipes and, thereby prevented from lifting out of the channels when the strip is under the tension of the stretched carpet. The carpet must be removed from the strip before the latter can be turned or 90 lifted out of the channel.

Having thus described my invention, what I claim and desire to secure by Letters Patent is—

1. In a building construction, the combination with a concrete floor having a mortise, of a flooring strip insertible into the mortise, and means to prevent the lifting of the strip by pressure exerted in an upward direction by a floor covering, said means including a conduit lying in the mortise and 95 engaging the edge of said strip.

2. In a building construction, the combination with a concrete floor having a mortise, of a flooring strip insertible into the mortise, and means to prevent the lifting of the strip by pressure exerted in an upward direction by a floor covering, said means including a conduit lying in the mortise, and 100 said strip having a concaved edge to engage the conduit, said strip coöperating with the walls of the mortise to inclose conduits for 110 electric wires or the like.

3. In a building construction, the combination with a concrete floor having a mortise, of means forming chambers to receive conduits between the walls of the mortise, and a strip with edges conforming to the conduits and serving as a key to prevent the tension of a nailed covering from lifting 115 the conduit from the mortise.

4. In a building construction, the combination with a floor of concrete having mortises with undercut walls, of flooring strips adapted to be seated in said mortises and 120 having undercut edges engaging conduits laid against the walls of the mortise.

5. In a building construction, the combination of a floor of concrete, of flooring strips with grooved edges adapted to be 125

seated in said mortises, said edges engaging the outer surfaces of conduits laid against the walls of the mortises whereby the strip is locked against accidental removal.

5 6. In a building construction, the combination of a floor of concrete having a plurality of undercut mortises, of removable conduits resting against the walls of said mortises, and strips for retaining the before-mentioned conduits in their respective positions, said strips having undercut edges and one of the conduits engaging one of the edges of the strip to prevent the strip from being lifted by the tension of an attached covering.

10 7. In combination with a conduit, a flooring strip insertible within a mortise and having a concaved edge adapted to rest upon and partially inclose the outer wall of the conduit laid in said mortise.

15 8. A flooring construction including a cement floor provided with a plurality of channels having undercut side walls, a suitable reinforcing liner substantially covering

the surface of the walls of the channel, and 25 means for retaining conduits laid along the sides of the reinforcing liner, said means including a flooring strip concaved along one of its edges to rest upon the inclosed conduit.

30 9. A floor construction, comprising a cement floor having mortises; a removable flooring strip having edges fashioned to form in combination with the walls of the mortises, chambers; and conduits laid in the 35 chambers, the outer walls of the conduits and the fashioned edges of the flooring strip interlocking to hold the strip in position, and one edge of the strip being beveled to permit said strip to be swung into place in 40 the mortise.

In testimony whereof I have hereunto set my hand in the presence of two subscribing witnesses.
